UNITED STATES PATENT OFFICE.

GEORGE W. TAYLOR, OF QUINCY, MASSACHUSETTS, ASSIGNOR OF ONE-HALF
TO WALTER JENNEY, OF BOSTON, MASSACHUSETTS.

BOTTLE.

SPECIFICATION forming part of Letters Patent No. 596,463, dated December 28, 1897.

Application filed November 29, 1895. Serial No. 570,390. (No model.)

To all whom it may concern:

Be it known that I, GEORGE W. TAYLOR, a citizen of the United States, residing at Quincy, in the county of Norfolk and State 5 of Massachusetts, have invented a new and useful Improvement in Bottles, of which the following is a full, clear, and exact specification, reference being had to the accompanying drawings, forming a part of the specification, in explaining its nature.

The invention relates to a bottle provided with means whereby it may be filled but once and refilling prevented, and also to the manner in which the bottle is constructed.

15 The means for permitting the filling of the bottle and preventing the refilling comprises two independent balls, the inner or lowermost one of which is smaller than the upper and acts as a valve, and the uppermost one 20 of which acts to hold the lower or innermost on its seat in any position of the bottle from a horizontal to a perpendicular one. The inclines upon the upper part of the cavity holding the larger ball serve to permit the contents of the bottle to flow by the ball by preventing it from seating upwardly, and also act to cause the ball to be moved against the valve-ball when in a horizontal position and thus prevent the bottle from being partly 25 filled when upon its side. To locate these balls in the neck of the bottle, it is desirable that the bottle be made in two parts—namely, the body, with a portion of the neck, and the remainder of the neck, which comprises about 30 two-thirds its length—and these parts are permanently united to each other in any of the usual ways of uniting glass after the two balls have been secured to the neck portion. This is accomplished by means of a small 35 wire, preferably doubled and arranged to encircle the smaller ball and pass through a hole in the upper ball and about the top of the neck, the balls being drawn thereby against the neck. This serves two purposes.

40 It secures the balls to the neck portion during the subsequent uniting of the two parts of the bottle, and it also acts to hold the valve-ball from its seat during the filling of the bottle. After the bottle has been filled the wire is disengaged from both balls, allowing them to 45 separate and to drop to their lowest positions

in their holding-cavities, the lower ball then seating and the upper ball resting upon it. It will be understood, of course, that there is used in addition the usual cork or stopper for 55 permanently closing the bottle. There is enough play in the cavity to permit the balls to move sufficiently to allow the contents of the bottle to be poured from it, but after it has been emptied it cannot be refilled, as the 60 valve-ball is constantly held against the valve-seat in any position of the bottle at which it might be otherwise practical to fill or partially fill it.

I will now describe the invention in connection with the drawings, wherein—

Figure 1 is a view in vertical section of the two sections of the bottle before they have been united and showing the balls as attached to the neck-section. Fig. 2 is a view representing the two parts of the bottle as secured together and the balls as still held to the upper part of the neck, being the position which they occupy until after the bottle is filled. Fig. 3 represents the balls as released, 75 the lower one resting upon the valve-seat and the upper one bearing upon it. Fig. 4 is a view of one type of wire ball-holder. Fig. 5 is a view representing the application of inclines to the lower or valve ball. 80

A represents the body portion or section of the bottle as prepared for the reception of the neck-section B. It has the cavity a above the valve-seat a' of a size to receive the ball C, being, in fact, slightly larger than the ball, 85 excepting where the ball bottom upon the valve-seat. From this cavity extends a section d of the larger chamber or cavity D of a size, as a whole, larger than the upper ball E, the remaining part d' of this cavity being in 90 the neck-section. The neck-section B has, in addition to the part d' of the cavity D, the usual passage or outlet b, which is adapted to receive the customary closing-cork F.

To prepare the parts so that the balls may 95 be located in their respective cavities and the two sections may be united, the ball C is attached with the ball E to the neck-section, preferably by a wire c in one or more parts passing about it and through a small hole e 100 in the ball E to a point without or above the neck of the bottle, the wire serving to draw

the balls firmly against the ribs b' in the part d' of the cavity D. The parts so assembled are represented in Fig. 1, and the neck is then united to the body A by permanently joining 5 its under edge B' with the upper edge A' of the said section in any desired way and the bottle is then in a condition to be filled, the balls still being held by the wire or as represented in Fig. 2.

10 After the bottle has been filled the wire is drawn from the lowermost ball through the small hole in the upper ball, leaving both balls free in their respective cavities, the upper ball resting upon the lower and the 15 lower ball seating itself on the valve-seat.

Upon the reversal of the bottle to pour its contents therefrom the liquid flows about the balls and in the channels between the ribs b' . Any attempt to refill the bottle, however, 20 will be unsuccessful, as in any position which will permit the bottle to be filled the smaller ball is held to its seat by the larger ball, thus preventing liquid from entering the bottle, and the larger ball acts as a barrier in preventing 25 the employment of any means for the removal of the lower ball from the seat.

When in a horizontal position, the under edges of the ribs b' serve to cause the larger ball to move or roll toward the lower ball and 30 still maintain it seated.

I would say that I do not confine myself to a valve that shall be entirely spherical, as any mechanical equivalents for this ball C, as well as for the barrier and holding ball E, may 35 be used.

Fig. 4 represents one form of wire holder. It is made of two strands g g' , which are twisted to form the round sections g^2 g^3 g^4 . The ball C is held between the three sections, 40 being placed upon the middle one, the end one being bent against one side of it and the ring g^2 against the other side and the straight portions of the wire passing through the hole in the ball E. (See Fig. 1.)

45 It will be seen that the valve-ball acts to close the entrance to the bottle and that the larger or barrier ball serves not only to hold the valve-ball closed, especially when the bottle is inclined or in a horizontal position, 50 but also prevents the valve-ball from being reached or tampered with from without the bottle. It will also be noticed that this result is reached by making the upper ball larger than the lower and by so shaping its 55 holding-cavity and proportioning the ball to it that access to the lower ball is rendered practically impossible.

It will be understood that any equivalent

for the wire retaining device for holding the balls to the neck-section may be used, and also that the wire need not pass through a hole in the barrier-ball, especially if provided with three or more strands instead of two, in which case the strands will pass around the ball and serve to well hold it. The ball would then have no central hole.

While I have described the device as applicable to bottles, it will be understood that it is also applicable to any receptacle adapted to contain a liquid and having a neck.

I am aware of the patent to F. H. Hutchinson, No. 518,606, and that to W. B. and W. H. Rand, No. 520,219, and of the German patent, No. 64,526, to Levenq; but as the said references do not describe my manner of constructing a bottle, nor a bottle having a valve, balls, inclines, and ball-holding recesses arranged in the neck, as herein specified, I consider that they do not contain any of the essential features of my invention.

Having thus fully described my invention, I claim and desire to secure by Letters Patent of the United States—

1. As a means for holding the balls C, D in the upper part of their respective chambers a , D , a temporary wire holder having the ring-sections g^2 g^3 , g^4 adapted to receive and hold the lowermost ball as specified, and a straight section arranged to pass through a hole in the upper ball B and connect both balls with the upper part of the neck and bottle, as and for the purposes described.

2. The combination with a bottle having a neck provided with two chambers or cavities D , a , of unequal size, and the side walls of which chambers or cavities are integral with said neck, the upper and larger chamber or cavity D having the inclines or ribs b' in its upper portion, of the valve and barrier balls C, E, of unequal size, in said chambers and a holder for temporarily attaching said balls to the upper part of said neck with the valve-ball lifted from its seat, said holder consisting of a wire having the connected ring-sections g^2 , g^3 and g^4 to receive the lower ball and a straight portion or portions to pass through the upper ball; whereby the bottle may be filled, and whereby also, when the said temporary ball-holder has been removed, even partial refilling of the bottle will be prevented.

GEORGE W. TAYLOR.
